United States Patent Office.

JOSEPH H. BUCKLEY, OF NEW HAVEN, CONNECTICUT.

Letters Patent No. 62,933, dated March 19, 1867.

IMPROVEMENT IN HYDRANTS.

The Schedule referred to in these Letters Patent and making part of the same.

TO ALL WHOM IT MAY CONCERN:

Be it known that I, JOSEPH H. BUCKLEY, of New Haven, in the county of New Haven, and State of Connecticut, have invented a new Improvement in Hydrants; and I do hereby declare the following, when taken in connection with the accompanying drawings and letters of reference marked thereon, to be a full, clear, and exact description of the same, and which said drawings constitute part of this specification, and represent, in—

Figure 1, a vertical central section; and in

Figure 2, a plan of the valve-chamber.

My invention relates to an improvement in that class of hydrants commonly known as "drinking" or "yard hydrants," and consists in the manner of packing the valve-seat so that the packing of the valve also forms the packing between the socket and the seat, and combined with the arrangement of the waste-way from the valve-chamber.

To enable others skilled in the art to construct and use my improvement, I will proceed to describe the same as illustrated in the accompanying drawings.

A is the socket or water-way attached to the supply pipe at the proper distance from the surface of the ground; B the valve-chamber fitted to screw into the socket A; C the valve; *a* the packing, consisting of a ring of leather or similar flexible material, and set between the chamber B and socket A, so as to form a packing between the two, and at the same time extending inward so as to form a flexible seat for the valve C, as seen in the drawing. D is the valve-rod extending up through a tube, E, and stuffing-box, F, and held up by a spring, G, which is of sufficient power to sustain the weight of the valve and its rod. H is the outlet or nozzle through which the water passes. The tube E is enclosed in the usual manner. To draw water, the rod D is depressed by a lever acting upon its upper end in the usual manner or any convenient or known device, so as to depress the valve C, as denoted in red. This will permit the water to flow through the hydrant, and when the power which depressed the valve is removed the force of the water will close the valve, and when so closed the tube E would remain filled with water. To this there are great objections, and to avoid which I form a tube, I, through the chamber B, as seen in fig. 2, with a conical seat in the centre, as seen in fig. 1, through which the rod passes, and through the socket or otherwise form outlets *d*, corresponding to the tube I, so that the water which remains in the tube will pass out through the openings *d*, as denoted by the blue arrows, and in order to close the tube I, when the valve is open, so that no water may be unnecessarily wasted, I form a cone, *f*, upon the valve-rod, so that when the valve is depressed the cone will close the tube I, as denoted in red, fig. 1. It is frequently necessary to remove the valve-chamber from its socket, and to replace it again without injury to the valve or thread on the socket is extremely difficult. To overcome this difficulty, I form a funnel-shaped guide, L, fixed to the socket in any convenient manner so that the opening through the guide corresponds to the socket, and so that when the valve-chamber is to be inserted it is lowered down, and, striking the inner surface of the funnel in whatever position it may, it will be guided to its proper position in the socket.

I do not wish to be understood as broadly claiming a self-closing hydrant, neither do I broadly claim a hydrant provided with a self-opening waste-way; but having thus fully described my invention, what I do claim as new and useful, and desire to secure by Letters Patent, is—

The combination of the valve C, having its seat formed and packed in the manner described, with the chamber B, provided with waste passage or passages I, and the cone *f* on the valve-rod, when the said passage or passages I are united or arranged so as to form a central support for the valve-rod, substantially as herein set forth.
